UNITED STATES PATENT OFFICE.

WILLON PERCEVAL ALDERSON, OF TIMMINS, ONTARIO, CANADA.

MINERAL-SEPARATOR.

1,264,135.

Specification of Letters Patent. Patented Apr. 30, 1918.

Application filed February 19, 1916. Serial No. 79,330.

To all whom it may concern:

Be it known that I, WILLON PERCEVAL ALDERSON, of the village of Timmins, in the District of Temiskaming, in the 5 Province of Ontario, Canada, have invented certain new and useful Improvements in Mineral-Separators, of which the following is the specification.

My invention relates to improvements in mineral separators and the object of the invention is to devise a separator which will thoroughly separate the finer particles from the coarser particles of the pulp, in which the bearings of the separator are 10 located above the level of the pulp and therefore have a longer life, and in which the necessity for digging out accumulated pulp before starting the machine is obviated and it consists of a trough closed at 15 one end and tapered toward the opposite end, the tapered end being open and the closed end being provided with a slotted outlet intermediate of its height, a main shaft extending longitudinally centrally 20 through the trough, a pivot support for one end of the shaft, a support for the opposite end of the shaft and means for vertically adjusting such opposite end upon the support, a rotary conveyer carried by the 25 shaft within the trough and conforming to the shape thereof, that is, having a tapered forward end, the said conveyer comprising two series of segmental blades arranged to 30 form a double spiral, the end of each blade overlapping and spaced forwardly of the adjacent end of the next blade in the series, and means for driving the shaft supporting the conveyer as hereinafter more particularly explained by the following specification.

Figure 1, is a general perspective view of my separator.

Fig. 2, is an enlarged longitudinal section through Fig. 1.

Fig. 3, is an end elevation showing a portion of the trough with one side broken away and in section.

In the drawing like numerals of reference indicate corresponding parts in each figure.

1 is a trough comprising a horizontal portion 2 and a tapered portion 3, the tapered portion being provided with an open end 4. The opposite end of the trough 1 is provided with a closed end formed by the end plate 6 in which is located a slotted outlet

7 and a vertical slot 8 for a purpose which will hereinafter appear. The trough 1 is supported on suitable chair standards 9 and 10. 11 is a feed inlet. 13 is the conveyer shaft provided at one end with a bearing sleeve 14 having trunnions 15 resting in bearing recesses 16 formed in the bearing blocks 17 carried by the beam 18. 19 is an I-beam extending across the end of the trough against the outside face of the plate 6, and above the outlet slot 7. 20 is an angle bar secured to the plate 6 and to the top of the I-beam 19 so as to support the corresponding end of the trough. 21 is an inverted U-bracket bolted to the angle bar 20 and I-beam 19 and located opposite the center of the trough 1. The bracket 21 is provided with internal vertical guide-ways 22 and 23. 24 is a slide piece substantially U-shape in form, the vertical edge portions of which extend into the vertical guide-ways 22 and 23. 25 is a sleeve secured on the shaft 15. 26 and 27 are trunnions extending from the sleeve into bearing enlargements 28 and 29 formed in the side piece 24.

30 is a stem secured at its lower end in the enlargement 31 of the slide piece 24. The stem 30 is provided with a threaded upper portion which passes freely through an orifice 32 in the top bar of the bracket 21. 33 is a hand wheel screwed on to the upper threaded end of the stem 30 so as to bear against the upper end of the bracket 21. 34 is the main driving shaft upon which is mounted a bevel gear 35 meshing with the bevel gear 36 carried by the shaft 13. The main shaft 34 is in axial alinement with the center of the trunnions 15. 37, 38 and 39 are spiders carried by the shaft 13. The spider 37 is slightly larger than the spider 38 which is considerably larger than the spider 39.

40 are bars secured to the outer ends of the arms of the spiders 37, 38 and 39. The portions 41 of the bars 40 converge slightly inwardly and the portions 42 of the bars 40 converge sharply together toward the tapered open end 4 of the trough 1 so as to present a conical formation. 43 are series of U-shape brackets carried by the portions 41 of the bars 40. The brackets 43 gradually increase in size toward the inner ends of the portions 41. 44 are brackets also U-shape in form secured to the portions 42 of the bars 40, the brackets

44 being substantially equal in size. 46 are series of segmental arc-shape blades, one end of each blade being secured to the rear arm of each bracket 43 supported by 5 the portions 41 of a bar 40 and at the opposite end to the forward arm of each bracket secured to the next adjacent bar 40. The blades are also arranged to form a double spiral around the portions 40 of the bars 41, 10 the end portion of each arc-shape segmental blade 46 being set in advance of the adjacent end of the next succeeding blade as is shown clearly in Fig. 2 of the drawings.

It will also be noticed on referring to Fig. 15 2 that the blades 46 increase gradually in width from the end of the conveyer toward the center or that portion carried by the spider 38. At this point in the conveyer the blades are a maximum width.

20 47 are a series of blades carried by the portion 42 of the bar 40. The blades 47 are substantially of the equal width and therefore conform to the general tapered formation of the conveyer extending from the 25 spider 38 to the open end 5 of the trough 1.

From the above description it will be seen that the outer periphery of the conveyer conforms in shape to the internal periphery of the trough 1. The ends of the blades 47 are 30 arranged in spiral formation and are spaced apart in a similar way to the blades 46 previously described.

At the extreme end or apex of the conveyer single blades 48 and 49 are employed 35 carried by the brackets 50 and 51 secured to the portions 42 of the bars 40.

Having described the principal parts involved in my invention I will briefly describe the operation of the same.

40 The pulp is fed through the inlet 11 into the trough and has a tendency to flow into the horizontal or deep portion of the trough 2. The conveyer revolves in the direction indicated by arrow in Fig. 2. As the conveyer revolves the advancing ends of the 45 blades 46 engage the pulp feeding it forwardly up the incline of the trough. As the blade continues to revolve the pulp passes from the end of the blade on to the 50 advancing end of the next adjacent blade situated slightly rearwardly and is then carried again forward. By this means as the pulp flows back from one blade to the next blade it loosens up allowing the fine particles to free themselves from the mass and 55 float into the liquid mixed with the pulp. This action is repeated as the pulp passes from one blade to the other until all the fine particles have been removed from the mass 60 as such mass is carried up the inclined portion 3 of the trough to the outlet 4. The mass after this separating operation has taken place consists of the coarser particles of pulp which are discharged through the 65 discharge orifice 4, such mass being drained

as it passes above the liquid level in the trough. Fine particles separated as above described are carried by the flow on the surface of the liquid rearwardly above the lower blades 46 and through the outlet slot 70

7. After the separator has been left to stand and a certain amount of pulp settles and remains in the bottom of the trough all that is necessary to do is to turn the hand wheel 33 so as to draw up the stem 30 and slide piece 75 24 and the corresponding end of the shaft 13 supported therein upwardly so as to clear the blades 46 from the mass. After the blades are carried clear of the mass they may be again gradually lowered by reversing 80 the motion of the hand wheel 33 so as to gradually engage the mass of pulp and carry it forwardly. If desired, of course, after each separating operation the conveyer may be left in the raised position so that 85 the blades will be clear of any pulp which may remain after settling in the bottom of the trough.

By my construction the digging out of the pulp is obviated, the machine being so constructed as to clear itself of the settled pulp at the beginning of each operation.

Also in such a machine as I have described the pulp is thoroughly loosened up allowing the liquid to mix freely therewith and the 95 lighter particles to separate themselves from the coarser and float to the surface of the liquid to a separate outlet while the coarser particles being carried in an opposite direction to a separate point of discharge. 100

What I claim as my invention is—

1. A mineral separator comprising a trough having a tapered portion at one end terminating in a discharge opening, a closure for the opposite end having a discharge orifice therein, a supporting structure, a suitably driven shaft extending longitudinally through the trough pivotally carried on the supporting structure at one end so as to swing in a vertical plane and 105 adjustably supported upon the supporting structure at the opposite end, and a spiral conveyer carried by the shaft having a tapered end conforming to the shape of the trough. 110

2. A mineral separator comprising a trough having a tapered end terminating in a discharge orifice and a closure for the opposite end having a discharge orifice, a conveyer 120 rotatably mounted within the trough to conform to the shape thereof and comprising a series of segmental arc-shape blades arranged in spiral form, the rearward end of each blade being set forwardly of the rear end of the next forward adjacent blade, and means for 125 raising the conveyer clear of the bottom of the trough.

3. A mineral separator comprising a trough having a tapered end terminating in a discharge orifice and having an inlet ori- 130

fice in the periphery thereof, a closure for the opposite end of the trough having a discharge orifice located intermediately of its height, a spiral conveyer rotatably mounted within the trough and conforming to the shape thereof comprising a series of segmental arc-shape blades arranged in spiral formation, the rear end of each blade being

spaced forwardly of the forward end of the next forward adjacent blade and U-shaped brackets having the adjacent forward and rear ends of the blades secured thereto.
